UNITED STATES PATENT OFFICE.

GEORGE W. KING, OF REDSTONE, PENNSYLVANIA, ASSIGNOR OF ONE-HALF
HIS RIGHT TO WILLIAM KING, OF SAME PLACE.

IMPROVEMENT IN KING-BOLTS.

Specification forming part of Letters Patent No. 173,797, dated February 22, 1876; application filed
January 10, 1876.

To all whom it may concern:

Be it known that I, GEORGE W. KING, of Redstone, in the county of Fayette, in the State of Pennsylvania, have invented a new and useful Improvement in Attachment for Carriages, &c.; and I do hereby declare that the following is a full and exact description thereof, reference being had to the accompanying drawings and to the letters of reference marked thereon.

My invention relates to an improvement in attachment for carriages, wagons, &c.; and consists in pivoting the bolster-plate to the bolster-pin, in combination with a pivoted brace, the latter being connected to the coupling-poles and axle.

To enable others skilled in the art to make and use my invention, I will proceed to describe its construction and operation.

In the accompanying drawings, which form part of my specification, Figure 1 is a top view or plan of my improvement. Fig. 2 is a front elevation of the front axle, bolster, and bolster-plate. Fig. 3 is an end view of the axle, bolster, bolster-plate, and side view of the coupling-poles and pivoted brace.

In the drawings, A represents the axle, which is furnished with a fifth-wheel, B, of ordinary construction, and a bolster-pin, C, to the upper end of which is pivoted a bolster-plate, D, at e. f represents the bolster. g represents the coupling-poles, to which is attached

a bar, h, having lugs i, between which is pivoted the curved end of a brace, J, through the front end of which passes the bolster-pin C, on the lower end of which is a screw-nut for the purpose of holding the brace J in position with relation to the axle. By this manner of pivoting the brace with relation to the coupling-pole g and the bolster-pin C, the axle can have its usual movements without destroying the efficiency of the brace J, and, by pivoting the bolster-plate to the upper end of the bolster-pin, the bed of the wagon resting upon the bolster will always retain a horizontal position, notwithstanding the axle may vary from a horizontal plane, as when passing over uneven roads.

It will be seen that the bolster-plate, king-bolt, and brace together constitute a merchantable attachment, which may be sold for application to vehicles already constructed.

What I claim as of my invention is—

The combination of the bolster f, the king-bolt pivoted thereto at its upper end and passing through the axle A, and the brace J pivoted below the pole g and connected to the lower end of the king-bolt, substantially as set forth.

GEORGE W. KING.
